(57) **CLAIM**

The ornamental design for a data card, as shown and described.

DESCRIPTION

FIG. 1 is a perspective view of a data card showing my new design;

FIG. 2 is a top plan view thereof, the bottom being a mirror image;

FIG. 3 is a front elevational view thereof;

FIG. 4 is a left elevational view thereof, the right being a mirror image;

FIG. 5 is a rear elevational view thereof;

FIG. 6 is a perspective view of a second embodiment of a data card showing my new design;

FIG. 7 is a front elevational view thereof;

FIG. 8 is a rear elevational view thereof (the top and bottom plan views being identical to FIG. 2 and the left and right elevational views being identical to FIG. 4);

FIG. 9 is a perspective view of a third embodiment of a data card showing my new design;

FIG. 10 is a front elevational view thereof; and,

FIG. 11 is a rear elevational view thereof (the top and bottom plan views being identical to FIG. 2 and the left and right elevational views being identical to FIG. 4).

1 Claim, 4 Drawing Sheets
